OYSTER DREDGE HOIST GEAR

Antonio Mazzella, New Haven, Conn.

Application December 15, 1950, Serial No. 201,035

2 Claims. (Cl. 37—55)

1

This invention relates to oyster and clam dredge hoisting gear used on oyster boats or dredges, and in particular a pair of booms pivotally mounted through universal joints on a head block on the deck of a boat with the booms supported intermediate of the length thereof by auxiliary booms and with the ends of the booms positioned to travel upwardly and inwardly whereby oysters and the like carried by dredges suspended from the ends of the booms by cables trained over pulleys in the ends of the booms and actuated by a windlass or engine, may be dumped upon receiving trays on the deck of a boat upon which the gear is mounted.

The purpose of this invention is to provide hoisting equipment for drawing oyster and clam dredges inwardly in which the dredges are elevated to positions above the deck of a boat by which they are carried and in which the dredges are drawn inwardly to positions over the deck as they are elevated.

Various devices have been provided for recovering oyster and clam dredges but where the dredges are elevated and at the same time drawn inwardly comparatively heavy and elaborate machinery and equipment is required and the upkeep thereof is costly. With this thought in mind this invention contemplates a comparatively simple super-structure mounted on the hull of a boat wherein with oyster and clam dredges suspended from the ends of booms by cables the booms are actuated by the cables to elevate the dredges and at the same time carry the dredges inwardly to positions above the deck of the boat as the dredges are recovered.

The object of this invention is, therefore, to improve and simplify the construction of oyster and clam dredge recovering equipment whereby dredges suspended at the sides of a boat may be drawn in and elevated by a single hoisting engine and dumped by tripping a hand operating lever.

Another object of the invention is to provide structure for clam dredge reclaiming and hoisting gear that may be constructed with beams, pulleys, cables and the like that are now available on the market.

Another object of the invention is to provide a dredge for scooping oysters in the bottom of the sea in which the oysters are scooped with the dredge in a horizontal position and dumped with the dredge in a vertical position.

A further object of the invention is to provide structure for clam dredge hoisting gear that may readily be incorporated in a boat in which the

2

gear is of simple and economical construction.

With these and other objects and advantages in view the invention embodies a pair of booms pivotally mounted on a boat, auxiliary booms extended upwardly from the deck of the boat and by which the booms are supported, a tubular mast, and cables extended from dredges through pulleys in the ends of the booms and downwardly through the mast to hoisting equipment in the hull of the craft.

Other features and advantages of the invention will appear from the following description taken in connection with the drawings wherein:

Figure 1 is a view showing a side elevation of an oyster boat with the dredge hoisting gear mounted thereon and with the gear illustrated in the dredging position.

Figure 2 is a similar view showing one of the dredges in the dumping position.

Figure 3 is a plan view of the dredge illustrated in Figure 1.

Figure 4 is a front elevational view of the dredge shown in Figures 1 and 2 showing the gear in the position in which the dredges are operating, and with one of the dredges omitted.

Figure 5 is a similar view showing the gear with the dredges in the unloading position.

Figure 6 is a detail showing a plan view of an end of one of the booms illustrating the pulleys therein.

Figure 7 is a similar detail looking toward one side of the boom.

Figure 8 is also a similar detail showing a bail of one of the dredges entering notches in an end of one of the booms.

Figure 9 is a plan view showing one of the dredges in the scooping position and with the door indicated in dotted lines.

Figure 10 is an end elevational view of the dredge as shown in Figure 9.

Figure 11 is a similar view showing a longitudinal section through the dredge being taken on line 11—11 of Figure 9.

Figure 12 is a cross section taken on line 12—12 of Figure 9 showing the segment for actuating the door of the dredge.

Figure 13 is a detail illustrating the latch for retaining the door in the closed position.

Figure 14 is a longitudinal section through the dredge showing the dredge suspended and with the door thereof open.

Figure 15 is a cross section through the dredge as shown in Figure 14.

Referring now to the drawings wherein like reference characters denote corresponding parts

the dredge hoisting gear of this invention includes a pair of booms 10 and 11 pivotally mounted through universal joints 12 and 13 on a head block 14 with the boom 10 supported by an auxiliary boom 15 on one side of the boat and the boom 11 supported by a similar auxiliary boom 16 on the opposite side. The upper end of the auxiliary boom 15 is connected to the boom 10 by a universal joint 4 and the lower end is connected by a universal joint 5 to an upright 6 on the deck of the boat. The auxiliary boom 16 is similarly connected with a universal joint 7 to the boom 11 and to an upright 8 by a universal joint 9 on the deck of the boat. The lower surfaces of the booms are provided with guides 17 and 18 that are spaced from the outer ends and the guides are positioned to guide bails of the dredges into notches of the booms in the unloading positions.

The outer ends of the booms are formed as illustrated in Figures 6, 7 and 8 and each boom is provided with right angularly disposed pulleys or sheaves 19 and 20 which are journaled on pins 21 and 22, respectively with the pulley 19 positioned between sections 23 and 24 on the booms and the pulley 20 between ears 25 and 26.

The booms are controlled by cables 27 and 28 that extend from dredges 29 and 30 over sheaves 20, around the sheaves 19 in the outer ends of the booms and then inwardly over a pulley block 31 on a tubular mast 32 through which the cables extend downwardly to a windlass 33 positioned in the hull of the boat, which is indicated by the numeral 34.

Receiving trays 35 and 36 are positioned on the deck of the boat and these trays are connected by hinges 37 and 38 positioned on the stern ends thereof to discharge chutes 39 and 40 also positioned on the deck of the boat. The receiving trays 35 and 36 are connected by cables 41 and 42 to the booms with the cables connected at points 43 and 44, trained over pulleys 45 and 46, respectively, on a cross bar or bridle 47, and extended around sheaves 48 and 49 on the deck of the boat. With the cables connected in this manner the receiving trays will be elevated, as shown in Figure 2 when the booms are actuated to the unloading positions. The receiving trays are, therefore, elevated by the booms to receive oysters from the dredges and are then dropped downwardly onto the chutes as the dredges are lowered to pick up another load. The discharge chutes 39 and 40 are supported on cross beams 50 and 51, as illustrated in Figure 2.

A platform 52 is provided on the mast 32 for an operator so that the dredges may readily be observed in all positions.

The boat is provided with a stand pipe 53 which has outlets extended over the chutes through which water is discharged at a pressure sufficient to flush off oysters on the chutes whereby the oysters are washed to the deck of the vessel.

The deck of the boat is provided with blocks 54 and 55 that are positioned to receive the booms, as illustrated in Figure 3 to retain the booms in the dredging positions. A frame 56 is mounted on the upper part of the mast and the ends of the frame are extended to engage the booms to limit the upward movement thereof so that the booms will stop with the dredges over the receiving trays 35 and 36.

The chutes 39 and 40 are provided with direction vanes 57 and 58 which are pivotally mounted so that they may be set at different

angles thereby providing means for distributing oysters uniformly over the deck of the boat.

With the parts arranged in this manner the booms 10 and 11 are lowered and the dredges 29 and 30 are suspended to pick up loads. When the dredges are filled the cables are hauled in by the windlass or a suitable hoisting engine until the bails 60 and 61 of the dredges engage the ends of the booms. The continued upward movement of the cables causes the boom to travel upwardly over the deck whereby the dredges are carried upwardly until the booms engage the stop frame 56. The dredges are then opened by the operator stationed on the platform 52 and the load is deposited on the receiving trays 35 and 36 with the trays in elevated positions. The oysters slide by gravity into the chutes 39 and 40 and are then flushed off by hydraulic pressure from the outlet pipes of the stand pipe 53. The vanes 57 and 58 are adjusted to evenly distribute the oysters over the deck of the vessel. After the dredges are dumped the cycle is repeated, the dredges being again lowered by slackening the cables whereby the booms travel downwardly over the sides of the boat to the dredging positions.

The dredges 29 and 30 being similar, the same reference numerals are applied to both. The dredge 29 is provided with a wall 64 having teeth 65 in the forward edge and a similar wall 66 is provided on the opposite side with the edges connected by end walls 67 and 68, the intermediate parts of which are provided with openings 69 and 70 and the openings are covered with wire mesh 71 and 72, respectively. The bail 60 is positioned with the ends pivotally mounted in openings 73 and 74 of the end plates 67 and 68, as shown in Figure 14, the ends being secured in the openings by bolts, nuts, or other suitable means. The dredge is provided with a perforated door 75 that is secured at the lower ends by hinges 76 and 77 and the door is secured in the closed position by a segment 78 that is pivotally mounted by a pin 79 on the wall 66, the pin extended through the wall and also through a guide 80 that extends over the segment. The segment is connected to the door 75 by a cable 81 which is connected to the segment at the point 82 and to bars 83 and 84 the opposite ends of which are connected to clips 85 and 86 on the door.

The segment 78 is provided with a handle 88 that is positioned to snap under a spring latch 89, and the handle 88, which is provided with an operating cord 90 is retained in the latch by a projection 91 on a rod 92 that is pivotally mounted in bearings 83 and 94 on the wall 66, and that is provided with a lever 95 by which it may be manually actuated.

With the parts arranged in this manner the lever 95 is turned upwardly to release the handle 88 when the dredges reach the dumping position above the receiving trays, as shown in Figure 2. After the oysters are dumped from the dredges the handles 88 are drawn downwardly by the cords 90 to close the doors whereby the handles snap under the spring latches, in which they are held by turning the levers 95 so that the parts 91 are extended as shown in Figure 13.

By this means the contents of the dredges are emptied from the lower ends with the dredges suspended in upright positions whereas in the conventional type of dredge the contents are emptied by inverting the dredge.

The dredges are formed with metal frames covered with wire mesh and the bails are pivotally

mounted to permit swinging from side to side. It will be understood that modifications may be made in the design and arrangement of the parts without departing from the spirit of the invention.

What is claimed is:

1. In a dredge hoisting gear, the combination which comprises a boat having a deck, a head block on the forward part of the deck, a mast extended upwardly from the deck of the boat, a pair of booms pivotally mounted through universal joints on the head block of the boat and positioned to extend over the sides of the boat, pulleys in the outer ends of the booms, a pulley block on the mast, a pair of dredges suspended by cables with the cables extended through the pulleys in the ends of the booms, over the pulley block on the mast and downwardly to the interior of the hull of the boat, hinged receiving trays mounted above the deck of the boat, discharge chutes positioned to receive products from the receiving trays, guide means pivotally mounted on the discharge chutes for evenly distributing products over the deck of the boat, cables connecting the receiving trays to the booms for elevating the ends of the receiving trays as the booms are elevated, blocks positioned on the deck of the boat for limiting downward movement of the booms, a stop positioned on the mast for limiting upward movement of the booms, and means for flushing products from the chutes. 25

2. In a dredge hoisting gear, the combination which comprises a boat having a deck, a head block on the forward part of the deck, a mast ex-

tended upwardly from the deck of the boat, a pair of booms pivotally mounted on the head block of the boat and positioned to extend over the sides of the boat, pulleys in the booms, a pulley block on the mast, a pair of dredges suspended by cables with the cables extended through the pulleys in the ends of the booms, over the pulley block on the mast and downwardly to the interior of the hull of the boat, 10 hinged receiving trays mounted above the deck of the boat, discharge chutes positioned to receive products from the receiving trays, guide means pivotally mounted on the discharge chutes for evenly distributing products over the deck 15 of the boat, cables connecting the receiving trays to the booms for elevating the ends of the receiving trays as the booms are elevated, blocks positioned on the boat for limiting downward movement of the booms, a stop for limiting upward 20 movement of the booms, and means for flushing products from the chutes.

ANTONIO MAZZELLA.
